INVENTOR

UNITED STATES PATENT OFFICE

95,905

DESIGN FOR A HAT

Oscar Friedman, New York, N. Y.

Application May 2, 1935, Serial No. 56,657

Term of patent 3½ years

To all whom it may concern:

Be it known that I, Oscar Friedman, a citizen of the United States of America, residing in Manhattan, county of New York, and State of New York, have invented a new, original, and ornamental Design for a Hat, of which the following is a specification, reference being had to the accompanying drawing, forming part thereof, wherein,

The dominant feature of my design resides in the arrangement of the strips of material stitched semi-circularly on the crown of the hat.

I claim:

The ornamental design for a hat, substantially as shown and described.

OSCAR FRIEDMAN.
